CLAIM

The ornamental design for a chair, as shown and described.

DESCRIPTION

FIG. 1 is a perspective view of my ornamental design;

FIG. 2 is a right elevation view of the ornamental design of FIG. 1;

FIG. 3 is a left elevation view of the ornamental design of FIG. 1;

FIG. 4 is a front elevation view of the ornamental design of FIG. 1;

FIG. 5 is a rear elevation view of the ornamental design of FIG. 1;

FIG. 6 is a top plan view of the ornamental design of FIG. 1;

FIG. 7 is a bottom plan view of the ornamental design of FIG. 1; and,

FIG. 8 is a perspective view of the ornamental design of FIG. 1 with broken lines showing cushions, which are shown for illustrative purposes only and form no part of the claimed design.
